UNITED STATES PATENT OFFICE.

RICHARD BRIGGS, OF BOSTON, MASSACHUSETTS.

DESIGN FOR THE ORNAMENTATION OF GLASSWARE.

SPECIFICATION forming part of Design No. 19,106, dated May 21, 1889.

Application filed March 28, 1889. Serial No. 306,177. Term of patent 14 years.

To all whom it may concern:

Be it known that I, RICHARD BRIGGS, a citizen of the United States, residing at Boston, in the county of Suffolk and State of Massachusetts, have invented and produced a new and original Design for the Ornamentation of Glass and other Ware, of which the following is a specification, reference being had to the accompanying drawings, in which—

- 10 Figure I is a bottom plan view of a glass dish having my design applied thereto. Fig. II is a cross-section thereof on the line II II, Fig. I.
15 1 is a large center star, which is surrounded by a wide circle, 2, of large angular figures formed by crossed tangential lines, and surrounding this wide circle is another circle, 3, of small angular figures, also formed by crossed tangential lines. Around the body of

the dish is a broad band, 4, having a flower 20 figure in the form of a wreath or circle, 5, surrounding a medallion, 6, presenting sprays 7 and flowers 8, extending in opposite directions. An ornamental edge or border, 9, surrounds the whole, having a chain, 10, of leaves. 25

My design is applicable to table glass and other ware, such as decanters, dishes, wines, finger and other bowls, goblets, and tumblers.

Having thus described my invention, the following is what I claim as new therein and desire to secure by Design Letters Patent:

The design for the ornamentation of glass and other ware, substantially as herein described and shown.

RICHARD BRIGGS.
